DESIGN FOR AN APRON

Joseph Nachman and Jack Nachman,
Philadelphia, Pa.

Application April 19, 1944, Serial No. 113,309

Term of patent 14 years

(Cl. D3—26)

To all whom it may concern:

Be it known that we, Joseph Nachman and Jack Nachman, citizens of the United States, residing at Philadelphia, in the county of Philadelphia and State of Pennsylvania, have invented a certain new, original, and ornamental Design for an Apron, of which the following is a specification, reference being had to the accompanying drawing, forming part thereof.

In the drawing is shown a front view of an apron embodying our invention.

The edges of the split apron define the outline of two large pockets.

We claim:

The ornamental design for an apron, substantially as shown and described.

JOSEPH NACHMAN.

JACK NACHMAN.
